UNITED STATES PATENT OFFICE.

CHARLES C. DODGE, OF BOSTON, MASSACHUSETTS.

HINGED LAST.

1,224,451.

Specification of Letters Patent.

Patented May 1, 1917.

Application filed December 5, 1914. Serial No. 875,630.

To all whom it may concern:

Be it known that I, CHARLES C. DODGE, a citizen of the United States, and resident of Boston, in the county of Suffolk and State 5 of Massachusetts, have invented certain new and useful Improvements in Hinged Lasts, of which the following is a specification.

This invention relates to hinged lasts, and consists in the various features of structure, 10 arrangement and co-operation hereinafter described and claimed.

Of the accompanying drawings, which illustrate one form in which the invention may be embodied:

15 Figure 1 represents a side elevation, partly in vertical section, of a hinged last in extended position.

Fig. 2 represents a similar view, omitting the toe and showing the heelpart in a different angular position as for removing the last 20 from a shoe.

Fig. 3 represents a top plan view of the hinge.

Fig. 4 represents a rear elevation of the 25 forepart without the hinge.

Fig. 5 represents a front elevation of the heelpart without the hinge.

Fig. 6 represents, on a smaller scale, a side 30 elevation of the hinge, broken lines indicating the extreme angular positions of the movable parts.

Figs. 7 and 8 are views similar to Figs. 1 and 2 respectively and show a modification. The modification is embodied in the 35 hinge, and consists in an arrangement of the spring which causes the forepart and heelpart to be returned in every instance to the position shown by Fig. 7.

Fig. 9 represents on a smaller scale a side 40 elevation of a hinge made according to Figs. 6 and 7, broken lines indicating the extreme angular positions of the movable parts.

Fig. 10 represents an elevation of a heelpart and rear portion of a forepart, dotted 45 lines representing another modified form of hinge.

The same reference characters indicate the same parts wherever they occur.

Referring first to the form shown on 50 Sheet 1, the forepart is indicated at 10 and the heelpart at 11. These parts have abutting portions, one of which portions has a cylindric external surface 12, and the other of which has a cylindric internal surface 13.

The abutting portion of the forepart is 55 formed with laterally separated chambers 14 for the reception of the pivotally connected portions of the hinge, and the abutting portion of the heelpart is formed with a chamber 15 for the reception of a spring. 60

The hinge comprises two principal members 16 and 17, portions of which are bent to form ears to take the pivot pins 18. These ears and pins are arranged in the chambers 14 of the forepart so as to be entirely concealed, said chambers being closed at the bottom and sides of the last and likewise closed at the top of the cylindric portion. The members 16 and 17, as shown, are in the form of plates or leaves, and the forepart and heelpart are therefore formed respectively with kerfs 19 and 20, and the extremities of the plates or leaves are arranged in said kerfs. The side edges of the hinge leaves as shown are flush with the surface of the last. Screws 21 and 22 are screwed from the bottom of the forepart and heelpart respectively through holes 21' and 22' formed in the leaves of the hinge, said screws coacting with the wood above and 75 below the leaves to draw the wood with clamping effect against the leaves. The screws are preferably of a length sufficient to reinforce the wood so as to compensate for the weakening due to the formation of 80

the kerfs 19 and 20. Screws of the proportions shown reinforce the wood to a degree more than that required to compensate for the loss of strength due to the kerfs, and enable the last to withstand very great torsional stress along a line parallel to the length of the last. The stock which is between the chambers 14 bears against the leaf 85 16 of the hinge, and the assembled structure is, to all intents and purposes, as solid and 90 strong to sustain hammer blows upon the bottom of the shank as if no stock were cut away as at 14, 14.

The members 16 and 17 are provided with confronting seats for a helical compression 100 spring 23, the seat on the member 16 being indicated at 26 and the seat on the member 17 being indicated at 27. The seats are formed with teat portions 28 which are arranged to project into the ends of the spring 105 to keep said ends upon their seats. That portion of the front leaf which extends to the rear of the hinge pin 18 and which is in-

dicated at 29 constitutes one member of a toggle, the other member of the toggle being the spring 25. When the forepart and heelpart are in the angular position shown by Fig. 1, the seat 26 is above a line intersecting the axis of the pin 18 and the seat 27, but when the forepart and heelpart occupy the angular position shown by Fig. 2 the seat 26 is below the said line. In Fig. 6 the seats 26 and 27 are indicated conventionally by dots. Broken lines a' and a^2 intersect the axis of the hinge and the seat 27 in the two positions of the latter, corresponding respectively to Figs. 1 and 2. Broken lines b' and b^2 represent the axis or line of thrust of the spring 25, the angular position of b' corresponding to the angular position of the spring in Fig. 1, and the angular position of b^2 corresponding to the angular position of the spring in Fig. 2. As the forepart and heelpart move from one position to the other, the distance between the seats 26 and 27 grows less until both of said seats and the axis of the hinge are on "dead center" or all in line with each other, and as the seats move out of said line the distance between them increases. The spring thus acts to hold the forepart and heelpart in both of their extreme positions, but is nevertheless capable of yielding to permit shifting said parts from one position to the other. The spring is entirely inclosed in the socket 15, which socket is open only at the side which is toward and closed by the forepart. As far as I am aware, I am the first to have provided a hinged last with hinge members one of which is arranged to act as a toggle member for the purpose explained; and I think I am the first, also, to have combined a connecting hinge and double acting holding means as a self-contained unit. My hinge and holding device are capable of being assembled in coöperative relation before they are put into a last; and this relation is not disturbed by setting them into the last. In Fig. 4 I have indicated filling pieces 19' for closing the extremities of the kerf 19 at the sides of the narrow part of the hinge.

When the forepart and heelpart are in the position shown by Fig. 1, the surfaces 30 of the member 17 abut against the surfaces 31 of the member 16 for the purpose of sustaining the lasting stresses and for relieving the abutting portions of the forepart and heelpart from undue stress. This may be better understood when it is explained that the last, when in lasting position, is inverted, the socket member 32 in the heelpart resting upon a heeljack (not shown), and the toe of the forepart resting upon a toejack (not shown). The pressure upon the last, due to pulling over the leather and to driving lasting tacks between the points directly over the two jacks, has a tendency to

"buckle" the hinge. In hinged lasts as hitherto made, the hinge-pin has been anchored directly in the wood, and the abutting portions 10' and 11' (Fig. 2) of the forepart and heelpart have been relied upon to sustain the stresses in question. The structure of my hinge relieves the wood of such stresses, the hinge-pins being in no way dependent upon the wood, and the surfaces 30 and 31 of the hinge members being arranged to abut against each other to sustain the stresses which would otherwise devolve upon the wood surfaces 10' and 11'.

Figs. 7, 8 and 9 illustrate in what manner the hinge already described may be modified so as to cause the forepart and heelpart to return in every case to the angular relation shown by Fig. 7. The only difference necessary to accomplish the result last mentioned is to set the spring seats farther forward with relation to the hinge pins than they are in the form first described. In Figs. 7, 8 and 9 the spring seats are indicated at 26' and 27'. The spring 25 in this form is the same as in the first form. By comparing Figs. 1 and 7 it may be seen that in the former the seat 26 is a considerable distance behind the center of the hinge pins, while in Fig. 7 the seat 26' is not so far behind the center. A corresponding difference obtains as to the location of the seats 27 and 27'. In consequence of arranging the spring seats as shown by Figs. 7, 8 and 9, the seat 26' never crosses the line which intersects 27' and the axis of the hinge pin. As shown by Fig. 9 the hinge is in its normal position, broken line a' being arranged to intersect the rear seat 27' and the axis of the hinge pin. Broken line b' represents the axis of the spring when the hinge is in its normal position. Broken line a^2 represents the angular position which would be taken by line a' when the forepart and heelpart are in the relation shown by Fig. 8. The point to be observed is that the seat 26' is so located that it is always outside the angle defined by lines a' and a^2 . Broken line b^2 represents the axis of the spring when the forepart and heelpart are in the relation shown by Fig. 8. In all other respects the hinge shown by Figs. 7, 8 and 9 is the same as that first described, and the same reference characters are used with the exception of those which indicate the spring seats.

The hinge indicated by dotted lines in Fig. 10 is the same as that shown by Figs. 7, 8 and 9 excepting that the front leaf 16' of the hinge is set at an angle which will cause it to occupy the forepart where the stock is thicker. The ball portion of the last shown is a substantial distance below the shank, and for this reason it might be desirable to incline the front leaf of the hinge as shown by Fig. 10. As the styles of lasts vary in this respect, the angle of the front

leaf of the hinge may be varied accordingly, to the end that such leaf may be arranged in the most desirable part of the last.

5 I claim:

1. A hinged last comprising a forepart, a heelpart, hinge-members connecting said parts, and a spring attached to said hinge-members and arranged to hold them in a plurality of angular positions.

2. A hinged last comprising a forepart, a heelpart, hinge-members connecting said parts, and a helical spring the ends of which are arranged to act upon two portions of said hinge-members to hold the latter in a plurality of angular relations, said portions being movable, one relatively to the other, to shift the effective line of spring stress across the "dead center" of the hinge.

20 3. A hinged last comprising a forepart, a heelpart, hinge-members connecting said parts, and a helical compression spring the ends of which are arranged to act upon two portions of said hinge-members to hold the latter in a plurality of angular relations, said portions being movable, one relatively to the other, to shift the effective line of spring stress across the "dead center" of the hinge.

25 4. A hinged last comprising a forepart, a heelpart, hinge-members connecting said parts, and a spring pivotally connected to both said hinge-members and arranged to hold them in a plurality of angular positions.

30 5. A hinged last comprising a forepart, a heelpart, hinge-members connecting said parts, and a spring arranged between said hinge-members to coact as a toggle with one of said members to hold said hinge members in two angular positions.

35 6. A hinged last comprising a forepart, a heelpart, hinge-members connecting said parts, and a helical compression spring arranged so that its ends bear against both of said members, the spring-engaging part of one of said hinge-members being arranged to act as one member of a toggle and said spring being arranged to act as the complementary toggle member, to hold said hinge members in two angular positions.

40 7. A hinged last comprising a forepart, a heelpart, hinge members connecting said parts, said hinge-members having spring seats confronting each other, and a compression spring seated upon said seats, one of said seats being arranged to pass between the axis of the hinge and the other seat and to cross the line intersecting said axis and said other seat.

45 8. A hinged last comprising a forepart, a heelpart, a hinge connecting said parts, and a helical compression spring the ends of which are seated on the two leaves of said hinge, each of said leaves having means for

keeping the spring on the seats thereof, said spring being arranged to hold said hinge-members in two angular positions.

9. A hinged last comprising a heelpart and a forepart movable about a transverse axis, pivotally connected hinge members for connecting said parts, and a spring having its ends seated against both the hinge members and arranged with its direction of normal thrust at one side of the "dead center."

10. A hinged last comprising a heelpart and a forepart movable about a transverse axis, pivotally connected hinge members for connecting said parts, and a spring having its ends seated against both the hinge members and arranged with its direction of normal thrust out of the plane of the said axis to hold the said parts in normal position.

11. A hinged last comprising a heelpart, a forepart, means connecting said parts so that they are capable of movement about a transverse axis located relatively remote from the bottom of the last, and a spring exerting pressure against said last parts and normally located in a line transverse to and on one side of said axis to hold the last parts in normal position, said spring being movable by relative movement of said last parts to a line on the other side of said axis to hold the last parts at an angle to each other.

12. A hinged last comprising a heelpart and a forepart movable about a transverse axis, a hinge whose members are movable about an axis substantially coincident with the first-mentioned axis, and a spring seated against both said hinge members and moved by one member into different angular relation to the other member when said last parts are moved about their axis of relative movement.

13. A last comprising a forepart, a heelpart, two co-operative hinge members pivotally connected with each other and affixed respectively to said forepart and heelpart, and a helical compression spring seated against both said members, said members having spring-engaging portions arranged to impart angular movement to said spring to shift the line of spring stress back and forth across the axis of said hinge members.

14. A last comprising a forepart, a heelpart, a hinge the leaves of which have flat plate portions, said plate portions being affixed to said forepart and heelpart respectively, and having confronting edges, and a helical compression spring the ends of which are arranged against said edges to hold said forepart and heelpart in operative position for lasting, said plate portions having seats for the ends of said spring.

15. A last comprising a forepart having a transverse kerf extending forwardly from its rear end, a heelpart having a transverse kerf extending rearwardly from its front end, a hinge consisting of plates pivotally

connected to each other, said plates being arranged in said kerfs and affixed to the forepart and heelpart respectively, and a helical compression spring the ends of which are seated upon confronting edges of said plates to hold said forepart and heelpart in a predetermined angular relation.

16. A hinged last comprising a heelpart and a forepart relatively movable about a transverse axis, said last parts having hinge-recesses, a hinge connecting said parts and comprising members fixed in said recesses, a coiled compression spring pivotally seated on both said hinge members, and means for retaining said spring on said seats.

17. A last hinge comprising two angularly movable members having hinge connection, said members having confronting seats for a spring, and a helical compression spring arranged between and bearing against said seats, said seats being arranged to move said spring laterally to shift its line of thrust

toward and from the axis of said hinge connection in consequence of relative angular movement of said members.

18. A hinged last comprising a forepart and a heelpart capable of relative angular movement about a transverse axis, two hinged members fastened respectively to said forepart and heelpart, said members having hinge-connection with each other on said axis, said members having confronting seats for a spring, and a helical compression spring arranged between and bearing upon said seats, the alinement of said seats being substantially at right angles to said axis and offset from the latter when said forepart and heelpart are in operative relation.

In testimony whereof I have affixed my signature, in presence of two witnesses.

CHARLES C. DODGE.
